E. G. GARTIN

FEEDING MECHANISM

Filed Dec. 22, 1922

Inventor:
Emile G. Gartin
by

Emile G. Gartin

attorney.

UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

FEEDING MECHANISM.

Application filed December 22, 1922. Serial No. 608,455.

My invention relates to feeding mechanisms, and more particularly to feeding mechanisms for rock drilling motors.

An object of my invention is to provide an improved feeding mechanism. Another object of my invention is to provide an improved and very compact feeding mechanism for rock drilling motors. A further object of my invention is to provide an improved fluid operated feeding mechanism for rock drilling motors in which the over-all length may be materially diminished while obtaining relatively long feed. Other objects and advantages of my invention will hereinafter more fully appear.

In the accompanying drawings I have shown for purposes of illustration one form which my invention may assume in practice.

In these drawings,—

Fig. 1 is a view partially in elevation, but mainly in central longitudinal vertical section with parts broken away, illustrating one embodiment which my invention may assume in practice.

Fig. 2 is a transverse vertical section on the line 2—2 of Fig. 1.

In the form of my invention which I have selected for purposes of illustration I have shown the same in combination with a percussive drilling motor 1, which motor is adapted to actuate a drill steel 2 and is provided with improved feeding mechanism hereinafter described.

The motor 1 is provided with lateral gibs 3, the opposite sides of which gibs are guided in ways 4 formed in a shell 5. Extending longitudinally of the shell and journaled in bearings 6 and 7 respectively at the opposite ends thereof, is a rotatable threaded shaft 8 which may be driven by a gear 9 and with this threaded shaft or screw a nut 10, suitably fixed to the motor 1, cooperates. Suitably attached to the shell 5 and herein formed integrally therewith is a cylinder member 12 in whose bore 13 a piston 14 provided with suitable packings 15 and 16 is reciprocable. For the purpose of preventing rotation of the piston during its reciprocation, various means may be employed, but herein, with a view to simplicity of illustration, I have shown a key member 17 carried by the piston 14 and cooperating with a longitudinal straight slot 18 cut in the wall of the cylinder bore 13. The piston member 14 is internally threaded as indi-

cated at 20 and these threads fit and cooperate with the threads upon a screw 21 which is journaled at its opposite ends in suitable bearings 22 and 23 formed in the opposite heads of the feeding mechanism. Fluid pressure may be alternatively supplied to opposite sides of the piston 14 by way of ports 24 and 25. A suitable valve 26 having a supply port 27 and an exhaust groove 28 which is arranged to communicate with a vent port 29 serves to supply and exhaust fluid in such manner as to cause opposite movements of the piston member 14. A pinion 30 is secured in non-rotative relation to the screw 21. It will be observed that the pinion 30 is larger than the gear 9. As a result, a given number of revolutions of the pinion 30 will produce a larger number of rotations of the gear 9. Advantage is taken of this fact by making the lead of the screw 21 materially greater than that of the screw 8 whereby the movements of the piston 14 will least be hindered by friction of the threads of the screw 21, and the reaction, during drilling, of the motor 1 upon the screw 8 tending to rotate the same, thereby diminished. It will be noted, moreover, that the maximum possible feed of the motor 1 is less than the maximum possible travel of the piston 14 and this permits a further variation in the leads of the screws.

From the foregoing description the mode of operation of my invention will be very clearly apparent. Assuming the valve 26 to be in the position indicated, it will be observed that fluid pressure is passed through the passage 24 to act upon the rear end of the piston 14. The latter will accordingly move forward in its cylinder 12 and will, by reason of the fact that it cannot itself rotate, cause rotation of the screw 21 and so of the pinion 30. The pinion 30 will in turn rotate the gear 9 and so effect rotation of the screw 8. The latter will cooperate with the nut 10 to cause longitudinal feeding movement of the motor 1. When it is desired to reverse the feed, the port 27 may be brought opposite the passage 25 and the groove 28 caused to communicate with the passage 24. The piston will then move in the opposite direction, the screw 21 will rotate in an opposite direction and the screw 8 will rotate in an opposite direction.

While I have in this application specifi-

cally described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

10. 1. The combination with a drilling motor, of feeding means therefor including relatively reciprocable and rotatable cooperating members, means for effecting reciprocating movement of said reciprocable member to effect rotary motion of said rotatable member, and means for transforming said rotary motion to a feeding motion and transmitting said feeding motion to said motor whereby continuous relative movement between said members in one direction effects forward feeding movement of said drilling motor while continuous relative movement between said members in the other direction effects retraction of said drilling motor.
20. 2. The combination with a drilling motor, of feeding means therefor including a rotatable screw, a piston operatively connected to said screw, a cylinder containing said piston, means for effecting relative motion between said screw and piston to effect movement of the former, and means for transforming the motion of said screw to a feeding motion and transmitting said feeding motion to said motor whereby continuous relative motion in one direction between said piston and screw effects forward feeding movement of said drilling motor while the opposite continuous relative movement effects retraction of said drilling motor.
30. 3. The combination with a drilling motor, of feeding means therefor including a screw, a reciprocable piston operatively connected to said screw, a cylinder containing said piston, means for effecting relative motion between said screw and piston to produce a movement of one of the same, and means for transforming said movement to a feeding motion and transmitting said feeding motion to said motor including a feed screw and a cooperating feed nut whereby continuous relative movement in either direction between said first mentioned screw and piston effects corresponding feeding movement of said motor.
40. 4. The combination with a drilling motor, of feeding means therefor including a screw, a reciprocable piston operatively connected to said screw, a cylinder containing said piston, means for effecting relative motion between said screw and piston to produce a movement of one of the same, and means for transforming said movement to a feeding motion and transmitting said feeding motion to said motor including a feed screw, a cooperating feed nut, and gearing connect-
50. ing said first mentioned screw with said feed screw whereby continuous relative movement in either direction between said first mentioned screw and said piston effects corresponding feeding movement of said motor. 70
60. 5. The combination with a drilling motor, of feeding means therefor including a screw member, a member cooperating therewith, means for effecting relative motion between said members to effect movement of one of the same, and means for transforming said movement to a feeding motion and transmitting said feeding motion to said motor including a feed screw and a cooperating feed nut whereby continuous relative movement in either direction between said members effects corresponding feeding movement of said motor. 75
70. 6. The combination with a drilling motor, of feeding means therefor including a screw, a reciprocable piston operatively connected to said screw, a cylinder containing said piston, means for effecting relative motion between said screw and piston to effect movement of one of the same, and means for transforming said movement to a feeding motion and transmitting said feeding motion to said motor including a non-rotatable feed nut carried by said motor, a rotatable feed screw cooperating therewith, and means operatively connecting said feed screw with said first mentioned screw whereby continuous relative movement in either direction between said first mentioned screw and piston effects corresponding feeding movement of said motor. 80
80. 7. The combination with a drilling motor and means for supporting said motor for feeding movement of a predetermined length, of feeding means for said motor including a screw, a reciprocable piston operatively connected to said screw, a cylinder containing said piston, means for effecting movement of said piston longitudinally of said screw to effect rotary motion of the latter, and means for transforming said rotary motion to a feeding motion and transmitting said feeding motion to said motor including means operatively connecting said screw and said motor whereby continuous relative movement in either direction between said screw and piston effects corresponding feeding movement of said motor. 100
90. 8. The combination with a drilling motor and means for supporting said motor for feeding movement of a predetermined length, of feeding means for said motor including a feed screw, a reciprocable piston operatively connected to said screw, a cylinder containing said piston, means for effecting longitudinal relative motion between said screw and piston to effect rotary motion of one of the same, and means for transforming said rotary motion to a feeding motion and transmitting said feeding motion to said motor. 110
100. 9. The combination with a drilling motor and means for supporting said motor for feeding movement of a predetermined length, of feeding means for said motor including a feed screw, a reciprocable piston operatively connected to said screw, a cylinder containing said piston, means for effecting longitudinal relative motion between said screw and piston to effect rotary motion of one of the same, and means for transforming said rotary motion to a feeding motion and transmitting said feeding motion to said motor. 115
110. 10. The combination with a drilling motor and means for supporting said motor for feeding movement of a predetermined length, of feeding means for said motor including a feed screw, a reciprocable piston operatively connected to said screw, a cylinder containing said piston, means for effecting longitudinal relative motion between said screw and piston to effect rotary motion of one of the same, and means for transforming said rotary motion to a feeding motion and transmitting said feeding motion to said motor. 120
120. 11. The combination with a drilling motor and means for supporting said motor for feeding movement of a predetermined length, of feeding means for said motor including a feed screw, a reciprocable piston operatively connected to said screw, a cylinder containing said piston, means for effecting longitudinal relative motion between said screw and piston to effect rotary motion of one of the same, and means for transforming said rotary motion to a feeding motion and transmitting said feeding motion to said motor. 125

- including means operatively connecting said screw to said motor whereby continuous relative movement in either direction between said screw and piston effects corresponding feeding movement of said motor.
9. The combination with a drilling motor, of feeding means therefor including a screw member, a nut member operatively connected to said screw member, means for moving one 10 of said members to effect motion of the other comprising a feed cylinder and a cooperating feed piston, and means for transforming said motion to a feeding motion and transmitting said feeding motion to said drilling 15 motor whereby continuous relative movement in either direction between said cylinder and piston effects corresponding feeding movement of said drilling motor.
10. The combination with a drilling motor, of feeding means therefor comprising a feed cylinder, a reciprocable piston contained therein, means for effecting relative motion between said cylinder and piston, and means deriving motion from such relative motion 20 for transmitting a feeding motion to said drilling motor at a rate different from the rate of relative motion aforesaid whereby continuous relative movement in one direction between said cylinder and piston effects 25 30 forward feeding movement of said motor while the opposite continuous relative movement effects retraction of said drilling motor.
11. The combination with a drilling motor, of feeding means therefor comprising a feeding motor having relatively fixed and movable parts of which the latter moves relative to the former in a direction parallel to the direction of feed and at a different rate from the rate of feed, means for effecting 35 40 relative motion between said feeding motor parts, and means deriving motion from said relative motion and transforming the derived motion to a feeding motion and transmitting said feeding motion to said drilling motor whereby continuous relative movement in either direction between said feeding motor parts effects corresponding feeding 45 movement of said drilling motor.
12. The combination with a drilling motor, of feeding means therefor including a plurality of cooperating parallel feed screws, a reciprocable member cooperating with one of said screws, means for effecting relative movement between said reciprocable member 50 55 and its cooperating screw to effect rotary motion of the latter, and means comprising means for transmitting rotary motion therefrom to the other screw and a nut operatively connected to the said other screw and carried by said motor for transforming said rotary motion to a feeding motion and transmitting said feeding motion to said motor whereby continuous relative movement in either direction between said reciprocable 60 65 member and its cooperating screw effects corresponding feeding movement of said motor.
13. The combination with a drilling motor, of feeding means therefor comprising a rotatable feeding screw, means for rotating said screw including a motor having relatively movable members one of which is reciprocable in a path parallel to the direction of feed, and means for transforming the rotary motion of said screw to a feeding motion and transmitting said feeding motion to said motor whereby continuous relative movement in either direction between said members effects corresponding feeding movement of said motor.
14. The combination with a drilling motor, of feeding means therefor including a screw, a nut operatively connected to said screw, means for effecting relative rotary motion between said nut and screw, a second screw disposed parallel to said first mentioned screw, and means comprising a nut cooperating with said second mentioned screw, and means connecting said first mentioned screw to said second mentioned screw for rotation at different angular speeds for transforming said rotary motion between said first mentioned screw and nut to a feeding motion and transmitting said feeding motion to said motor whereby continuous relative movement in either direction between said first mentioned screw and nut effects corresponding feeding movement of said motor.
15. The combination with a drilling motor, of feeding means therefor comprising a plurality of cooperating relatively rotatable parallel shafts, a member cooperating with one of said shafts and movable longitudinally thereof, means for effecting rotary motion between said member and its cooperating shaft, and means for transmitting the rotary motion to the other shaft and transforming the rotary motion of the latter to feeding motion and transmitting said feeding motion to said motor whereby continuous relative movement in either direction between said member and its cooperating shaft effects corresponding feeding movement of said motor.
16. The combination with a drilling motor, of feeding means therefor comprising a rotatable shaft, a piston cooperating with said shaft and movable longitudinally thereof, a cylinder containing said piston and within which said last mentioned shaft is supported, means for admitting pressure fluid to said cylinder to effect relative motion between said piston and said last mentioned shaft to produce a movement of one of the same, and means including a rotatable shaft parallel with said first mentioned shaft and rotatable relative thereto for transforming said movement to a feeding motion and transmitting said feeding motion to said

- motor whereby continuous relative movement in either direction between said piston and its cooperating shaft effects corresponding feeding movement of said motor.
17. The combination with a drilling motor and guiding means therefor, of feeding means for said motor including a screw, a reciprocable feed piston cooperating therewith, a feed cylinder carried by said guiding means and containing said piston, a second screw arranged parallel with said first mentioned screw and operatively connected to the latter, means for effecting relative motion between said feed piston and said first mentioned screw to produce a movement of the second screw, and means comprising a feed nut carried by said motor and cooperating with said second mentioned screw for transforming said movement to a feeding motion and transmitting said feeding motion to said motor whereby continuous relative movement in either direction between said piston and said first mentioned screw effects corresponding feeding movement of said motor.
18. The combination with a drilling motor and guiding means therefor, of feeding means for said motor comprising a cylinder

carried by said guiding means, a reciprocable piston disposed in said cylinder and held against rotatable movement relative thereto, a rotatable screw arranged coaxially within said cylinder and journaled on said guiding means and with which said piston cooperates, means whereby pressure fluid may be admitted to said cylinder to effect longitudinal movement of said piston relative to said screw to effect rotary motion of the latter, and means for transforming said rotary motion to a feeding motion and transmitting said feeding motion to said motor including a second rotatable screw arranged parallel with said first mentioned screw and journaled on said guiding means, a nut carried by said drilling motor with which said second mentioned screw cooperates, and means for operatively connecting said first mentioned screw with said second mentioned screw, whereby a continuous relative movement in either direction between said piston and said first mentioned screw effects corresponding feeding movement of said motor.

In testimony whereof I affix my signature.

ELMER G. GARTIN.
